RAILWAY SIGNALING SYSTEM

George R. Pflasterer, Swissvale, Pa., assignor to
The Union Switch & Signal Company, Swiss-
vale, Pa., a corporation of Pennsylvania

Application June 22, 1937, Serial No. 149,655

9 Claims. (Cl. 246—50)

My invention relates to railway signaling systems of the type involving light signals wherein the signals each comprise a plurality of lamps and wherein when one lamp of a signal becomes 5 burned out another lamp of that signal will become lighted to display a more restrictive indication.

The apparatus provided by this invention is an improvement on the apparatus shown and 10 claimed in the application of Leon D. Dickinson and David C. Bettison, for Light-out protection circuit, Serial No. 225,372, filed August 17, 1938.

One object of my invention is to provide a signaling system wherein a distinctive "permissive" 15 indication is displayed at the entrance to an occupied block so that a train may enter such block without stopping and wherein a "stop" indication is displayed if the "permissive" indication is not displayed when it should be.

Other objects of my invention will become 20 apparent as the specification progresses.

I shall describe several forms of railway signaling systems embodying my invention, and shall then point out the novel features thereof in 25 claims.

In the accompanying drawings, Figs. 1A and 1B are diagrammatic views which, when placed end to end in the order named, illustrate one form of apparatus embodying my invention. 30 Figs. 2 and 3 are diagrammatic views each illustrating a different modification of a portion of the apparatus shown in Fig. 1A, and each also embodying my invention.

Similar reference characters refer to similar 35 parts in each of the several views.

Referring first to Figs. 1A and 1B, the reference characters 5 and 6 designate the rails of a stretch of railway track over which traffic normally moves in the direction indicated by the 40 arrows. The rails 5 and 6 are divided by insulated joints 7 into a plurality of sections of which sections W—X and X—Y are representative sections. Each section is further divided, as here shown, into two subsections 1T, 2T, 3T, etc. Each 45 subsection is provided with a track battery 8 connected across the rails at one end of the subsection and with a track relay, designated by the reference character TR with a prefix the same as the prefix in the reference character for the 50 associated subsection, connected across the rails at the other end of the subsection.

Located adjacent the entrance end of each track section is a signal designated by a suitable distinguishing reference character. As here 55 shown, each signal includes a proceed lamp G

capable of displaying a green light, a caution lamp Y capable of displaying a yellow light, and a stop lamp R capable of displaying a red light.

Each signal is provided with a polarized signal control relay, preferably of the retained neutral 5 type, and designated by the reference character HD with a prefix the same as the reference character of the associated signal.

Each signal control relay HD is connected to a pair of line conductors each including a front 10 contact of each of the associated track relays and each extending to the signal next in advance. As will be explained more in detail hereinafter, each pair of line conductors is reversibly governed by the apparatus associated with the 15 signal next in advance.

Each signal is provided with two direct current lightout relays designated by the reference characters GLO and YLO each with a prefix the same as the reference character of the associated signal. Each relay GLO is provided with two windings 13 and 14 and each relay YLO is provided with two windings 15 and 16.

Each signal is provided with an auxiliary relay designated by the reference character F with a 25 prefix the same as the reference character of the associated signal. Each relay F is provided with a control circuit which includes its own back contact so that whenever the control circuit is energized the associated relay F becomes periodically picked up and released. As will be explained more in detail hereinafter, the relays F are utilized at times to open and close periodically the lighting circuit for the caution lamp Y 30 of the associated signal so that that signal will 35 display a flashing aspect.

Each signal is provided with a suitable source of direct current and with a suitable source of alternating current, the terminals of which are designated by the reference characters B and C, 40 and BX and CX, respectively.

For governing the character of the current supplied to the signal lamps, each signal is provided with an alternating current power-off relay 45 designated by the reference character PO with a prefix the same as the reference character of the associated signal. That is, the current for lighting the signal lamps is supplied from terminals BX and CX or B and C according as the 50 associated relay PO is picked up or released, respectively. Since the relays PO are directly connected to the terminals BX and CX, it follows that the lamps of the associated signal are normally lighted by alternating current but will 55

be lighted by direct current whenever the alternating current is absent at that signal.

Having thus described in general the apparatus shown in Figs. 1A and 1B, I shall now describe the operation of the system.

- Each of the signals and associated apparatus is controlled by the associated relay HD in the following manner: When relay HD is deenergized (see signal 11), relay 11F is periodically energized by a circuit which passes over a path from terminal B through back point of contact 18 of relay 11HD, back contact 19 of relay 11F, and relay 11F to terminal C, with the result that relay 11F is repeatedly picked up and released. Consequently, lamp Y is periodically energized to cause signal Y to display a flashing yellow light to indicate "proceed with caution—block occupied". The circuit for lamp Y may be traced over a path which passes from terminal BX through front point of contact 20 of relay 11PO, back point of contact 21 of relay 11HD, front contact 22 of relay 11F, winding 15 of relay 11YLO, lamp Y of signal 11, and front point of contact 23 of relay 11PO to terminal C. Asymmetric unit 24 is connected around winding 15 to by-pass each half wave of alternating current so that relay 11YLO, although of the direct current type, will be effectively energized by alternating current as well as by direct current. Winding 13 of relay 11GLO and winding 16 of relay 11YLO are provided in a similar manner with asymmetric units 25 and 26, respectively, for the same purpose. When relay 11HD is released, winding 14 of relay 11GLO is also energized by a circuit which passes from terminal B through back point of contact 27 of relay 11HD and winding 14 of relay 11GLO to terminal C so that this relay is maintained in its picked up condition.
- When relay HD is energized in the reverse direction (see signal 10), a circuit is established for steadily energizing lamp Y of that signal to cause the signal to display a steady yellow light to indicate "proceed with caution—one block clear". This circuit may be traced over a path which passes from terminal BX through front point of contact 28 of relay 10PO, front point of contact 29 of relay 10HD, reverse polar contact 30—31 of relay 10HD, winding 15 of relay 10YLO, lamp Y of signal 10, and front point of contact 32 of relay 10PO to terminal BX. Relay 10YLO is, of course, in its picked up condition because winding 15 is included in the circuit for lamp Y, and relay 10GLO is also in its picked up condition because its winding 14 is energized by a circuit which passes over a path from terminal B through front point of contact 33 of relay 10HD, reverse polar contact 34—35 of relay 10HD, and winding 14 of relay 10GLO to terminal C.
- When relay HD is energized in the normal direction (see signal 9), a circuit is established for energizing lamp G of signal 9 so that the signal is displaying a green light to indicate "proceed at normal speed—two blocks clear". This circuit may be traced over a path which passes from terminal BX through front point of contact 36 of relay 9PO, front point of contact 37 of relay 9HD, normal polar contact 30—38 of relay 9HD, winding 13 of relay 9GLO, lamp G of signal 9, and front point of contact 39 of relay 9PO to terminal CX. Relay 9GLO is maintained in its picked up condition because its winding 13 is included in the circuit for lamp G, and relay 9YLO is maintained in its picked up condition because its winding 16 is energized

by a circuit which passes over a path from terminal BX through front point of contact 36 of relay 9PO, front point of contact 37 of relay 9HD, normal polar contact 30—38 of relay 9HD, front point of contact 40 of relay 9GLO, winding 15 of relay 9YLO, and front point of contact 39 of relay 9PO to terminal CX.

A train K, here shown diagrammatically, is occupying the section immediately to the right of location Y so that relay 11HD is deenergized with the result that relay 10HD is energized in the reverse direction by a circuit which passes over a path from terminal B at signal 11 through back point of contact 41 of relay 11HD, front contact 42 of relay 4TR, front contact 43 of relay 3TR, relay 10HD, front contact 44 of relay 3TR, front contact 45 of relay 4TR, and back point of contact 46 of relay 11HD to terminal C at signal 11.

Relays 10HD and 10YLO being both energized, relay 9HD is energized in the normal direction by a circuit which passes over a path from terminal B at signal 10 through front point of contact 47 of relay 10YLO, front point of contact 48 of relay 10HD, front contact 49 of relay 2TR, front contact 50 of relay 1TR, relay 9HD, front contact 51 of relay 1TR, front contact 52 of relay 2TR, front point of contact 53 of relay 10HD, and front point of contact 54 of relay 10YLO to terminal C at signal 10.

Since both relay 9HD and relay 9YLO are energized, the line circuit to the rear of location W is energized in the normal direction over front points of contacts 55 and 56 of relay 9YLO and front points of contacts 57 and 58 of relay 9HD so that the relay HD (not shown) controlled by that line circuit is in condition to cause its signal (not shown) to display the normal proceed indication.

In the event that the lamp Y at signal 11 becomes burned out, energy will be disconnected from winding 15 of relay 11YLO so that this relay will become released to establish a circuit for the lamp R of signal 11 to cause that signal to display a red light to indicate "stop". The circuit for lamp R may be traced over a path which passes from terminal BX through front point of contact 20 of relay 11PO, back contact 60 of relay 11YLO, reactor 61 of signal 11, lamp R of signal 11, and front point of contact 23 of relay 11PO to terminal CX. The reactor 61 is of substantially the same reactance as windings 13 and 15 of relays 11GLO and 11YLO, respectively, and is provided to equalize the voltage applied to lamp R with that applied to lamps G and Y. In a similar manner, if the lamp Y at signal 10 becomes burned out, relay 10YLO will become released to close a circuit for lamp R of signal 10 over back contact 62 of relay 10YLO so that signal 10 will be caused to display the "stop" indication.

If the lamp G at signal 9 becomes burned out, relay 9GLO will become released to establish a circuit for lamp Y because energy will be disconnected from winding 13 of relay 9GLO. This circuit may be traced over a path which passes from terminal BX through front point of contact 36 of relay 9PO, front point of contact 37 of relay 9HD, normal polar contact 30—38 of relay 9HD, back point of contact 40 of relay 9GLO, winding 15 of relay 9YLO, lamp Y of signal 9, and front point of contact 39 of relay 9PO to terminal CX. In the event that lamp Y of signal 9 then becomes burned out to release relay 9YLO, lamp R of signal 9 will become lighted over back contact 63 of relay 9YLO.

It will be noted that whenever any of the relays YLO becomes released, the line circuit to the rear becomes energized in the reverse direction if such line circuit is not already so energized. For example, if relay 10YLO becomes released, the direction of energization of the line conductors for section W-X will be changed to the reverse direction over the back points of contacts 47 and 54 of relay 10YLO so that signal 9 will be caused to display a "caution" indication.

Thus, it will be seen that if the green lamp of a signal is burned out when it should be lighted, that signal will be caused to display a "caution" indication, and if the yellow lamp of a signal is burned out when it should be lighted, that signal will be caused to display a "stop" indication and the signal next in rear will be caused to display a "caution" indication.

The retained neutral characteristic of the polarized relays HD prevents tumble-down of the signal control circuits to the rear during pole changing periods. For example, when the train K vacates the section to the right of location Y so that the energization of relay 10HD is changed from the reverse direction to the normal direction, the front points of neutral contacts 48 and 53 of relay 10HD do not become opened and, consequently, the energization of the line circuit for section W-X is not disturbed.

The slow releasing characteristic of relays GLO and YLO prevents the release of these relays when energy is transferred from one winding to another. For example, when the direction of energization of relay 10HD is changed so that energy is disconnected from winding 13 and applied to winding 14 of relay 10GLO, this relay, due to its slow acting feature, does not become released. The slow releasing characteristic of the relays YLO also prevents the release of these relays when the associated winding 15 is being periodically energized such, for example, as occurs when the apparatus is in the condition as shown in Fig. 1B.

Referring next to Fig. 2, it will be understood that although I have shown only one signal and associated apparatus, such signal and apparatus when connected in a system will function in a manner somewhat similar to that described for the apparatus shown in Figs. 1A and 1B. The principal difference in the two schemes is in the character of the indications displayed by the signal. In the present figure, the signal will display a green light to indicate "proceed at normal speed—two blocks clear", a yellow light over a yellow light to indicate "proceed with caution—one block clear", a yellow light to indicate "proceed with caution—block occupied", and a red light to indicate "stop".

When relay HD is energized in the normal direction as shown in the drawings, a circuit is established for winding 16 of relay YLO which circuit may be traced over a path which passes from terminal BX through front point of contact 65 of relay PO, front contact 66 of relay HD, normal polar contact 67-68 of relay HD, winding 16 of relay YLO, and front point of contact 64 of relay PO to terminal CX.

Relay HD and relay YLO both being energized, a circuit is established for lamp G which circuit may be traced over a path which passes from terminal BX through front point of contact 65 of relay PO, front point of contact 70 of relay YLO, reactor 71, front contact 72 of relay HD, lamp G, and front point of contact 69 of relay PO to terminal CX.

When relay HD becomes energized in the reverse direction, a circuit will be established for lamp Y which circuit passes over a path from terminal BX through front point of contact 65 of relay PO, front point of contact 73 of relay HD, reverse polar contact 74-75 of relay HD, winding 15 of relay YLO, lamp Y, and front point of contact 69 of relay PO to terminal CX. Although energy will be disconnected from winding 16 of relay YLO by the opening of normal polar contact 67-68 of relay HD, relay YLO will remain in its picked up condition to maintain the previously traced circuit for lamp G because winding 15 of relay YLO is connected in series with lamp Y.

When relay HD becomes deenergized, another circuit will be established for lamp Y and the circuit for lamp G will become opened. This circuit for lamp Y may be traced over a path which passes from terminal BX through front point of contact 65 of relay PO, back point of contact 73 of relay HD, winding 15 of relay YLO, lamp Y, and front point of contact 69 of relay PO to terminal CX.

In the event that lamp Y should become burned out, energy will be disconnected from winding 15 of relay YLO so that a circuit would be closed for lighting lamp R. This circuit passes over a path from terminal BX through front point of contact 65 of relay PO, back point of contact 70 of relay YLO, reactor 76, lamp R, and front point of contact 69 of relay PO to terminal C.

The line circuit to the rear is controlled in a manner similar to that described for the line circuit shown in Figs. 1A and 1B. That is, when both relays HD and YLO are energized, the rear line circuit is supplied with energy in the normal direction, but when either relay HD or relay YLO is deenergized, the rear line circuit is supplied with energy in the reverse direction.

Referring now to Fig. 3, it will be understood that the single signal and associated apparatus will, when connected in a system, function in a manner somewhat similar to that described for the apparatus shown in Figs. 1A and 1B. The principal difference between the two schemes is in the character of the indications displayed by the signal. In the present figure, the signal displays a green light over a green light to indicate "proceed at normal speed—two blocks clear", a single green light to indicate "proceed with caution—one block clear", a yellow light to indicate "proceed with caution—block occupied", and a red light to indicate "stop".

When relay HD is energized in the normal direction, as shown in the drawings, circuits are established for both the upper and lower signal lamps G. The circuit for upper lamp G may be traced over a path from terminal BX through front point of contact 78 of relay PO, front point of contact 79 of relay HD, winding 13 of relay GLO, upper lamp G, and front point of contact 80 of relay PO to terminal CX. The circuit for lower lamp G may be traced over a path from terminal BX through front point of contact 78 of relay PO, front point of contact 81 of relay HD, normal polar contact 82-83 of relay HD, reactor 84, lower lamp G, and front point of contact 80 of relay PO to terminal CX.

Relay GLO is maintained in its picked up condition because winding 13 is connected in series with upper lamp G and relay YLO is maintained in its picked up condition because winding 15 is energized by a circuit which may be traced over

a path passing from terminal BX through front point of contact 78 of relay PO, front point of contact 81 of relay HD, winding 15 of relay YLO, and front point of contact 80 of relay PO to terminal CX.

When relay HD becomes energized in the reverse direction, the circuit for lower lamp G will be opened at normal polar contact 82-83 of relay HD, but the previously traced circuits for both the upper lamp G and winding 15 of relay YLO will remain closed. In the event that the upper lamp G becomes burned out, so that energy is disconnected from winding 13 of relay GLO, another circuit for lower lamp G will be come established so that the signal will continue to display a single green light. This circuit passes over a path from terminal BX through front point of contact 78 of relay PO, front point of contact 79 of relay HD, back contact 85 of relay GLO, reactor 84, lower lamp G, and front point of contact 80 of relay PO to terminal CX.

When relay HD becomes deenergized, a circuit will be established for lamp Y which circuit passes over a path from terminal BX through front point of contact 78 of relay PO, back point of contact 81 of relay HD, winding 16 of relay YLO, lamp Y, and front point of contact 80 of relay PO to terminal CX. Relay YLO will be maintained in its picked up condition because winding 16 is included in the circuit for lamp Y and relay GLO will be maintained in its picked up condition because winding 14 will be energized by a circuit which passes from terminal BX through front point of contact 78 of relay PO, back point of contact 79 of relay HD, winding 14 of relay GLO, and front point of contact 80 of relay PO to terminal CX.

In the event that lamp Y becomes burned out, energy will be disconnected from winding 16 so that relay YLO will be released to establish a circuit for lamp R to cause the signal to display a red light. This circuit may be traced over a path which passes from terminal BX through front point of contact 78 of relay PO, back contact 86 of relay YLO, reactor 87, lamp R, and front point of contact 80 of relay PO to terminal CX.

The line circuit to the rear is reversibly governed by the relays HD and YLO in a manner similar to that described for the apparatus shown in the other figures, and it is believed that this will be obvious from the drawings without further explanation.

From the foregoing description of the apparatus embodying my invention, it will be seen that I have provided a signal system wherein a distinctive "permissive" aspect is displayed at the entrance to an occupied block so that a following train may enter such block without stopping and wherein a "stop" aspect is displayed if the permissive aspect is not displayed when it should be. Furthermore, I have provided control circuits for the signal next in rear which circuits function in such a manner that the rear signal will be caused to display a restrictive aspect whenever the signal next in advance is displaying its stop aspect regardless of the condition of the signal control relay associated with such advance signal.

Although I have herein shown and described only a few forms of railway signaling systems embodying my invention, it is understood that various changes and modifications may be made therein within the scope of the appended claims

without departing from the spirit and scope of my invention.

Having thus described my invention, what I claim is:

1. In combination, a section of railway track, 5 a signal for said section including a first lamp and a second lamp, a circuit for energizing said first lamp when said section is occupied, a relay having two windings, one winding of said relay being included in said circuit, means for energizing the other winding of said relay when said section is unoccupied, and a circuit for said second lamp including a back contact of said relay.

2. In combination, a section of railway track, 15 a signal for said section including a first lamp and a second lamp, a relay having two windings, means for energizing one winding of said relay when said section is unoccupied, means for energizing said first lamp when said section is occupied and for simultaneously energizing the other winding of said relay provided the filament of said first lamp is then intact, and means for energizing said second lamp if and only if said relay is released.

3. In combination, a section of railway track, 25 a signal for said section, a control relay for controlling said signal, means for energizing or de-energizing said relay according as said section is unoccupied or occupied respectively, a first lamp for said signal, means for energizing said first 30 lamp when said control relay is energized, a second lamp for said signal, means for energizing said second lamp when said relay is deenergized, an auxiliary relay having two windings, means for energizing one of said windings when said 35 control relay is energized, means for energizing the other of said windings when said control relay is deenergized provided the filament of said second lamp is intact, a third lamp for said signal, and means for lighting said third lamp if and only 40 if said auxiliary relay becomes deenergized.

4. In combination, a plurality of successive sections of railway track, a signal for each section each including a first lamp, a second lamp and a third lamp, a relay for each section each including two windings, means for each section for simultaneously energizing the associated first lamp and one winding of the associated relay when that section is unoccupied, a circuit for each section including the associated second lamp and the other winding of the associated relay in series, means for each section for energizing the associated circuit when that section is occupied, and means for each section for energizing the associated third lamp when the associated relay is de-energized. 45 50 55

5. In combination, a plurality of successive sections of railway track, a signal for each section each including a first lamp, a second lamp and a third lamp, a relay for each section each including two windings, means for each section for simultaneously energizing the associated first lamp and one winding of the associated relay when that section is unoccupied, a circuit for each section including the associated second lamp and the other winding of the associated relay in series, means for each section for energizing the associated circuit when that section is occupied, means for each section for energizing the associated third lamp when the associated relay is deenergized, and means for each section governed by the associated relay for at times governing the signal for the section next in rear. 60 65 70

6. In combination, a section of railway track, a signal for said section including a proceed 75

- lamp, a caution lamp and a stop lamp, a polarized signal control relay which becomes deenergized when said section is occupied but which is energized in the normal or reverse direction in accordance with traffic conditions in advance when said section is unoccupied, a first lightout relay having two windings, a second lightout relay also having two windings, a circuit for said proceed lamp including a front contact and a normal polar contact of said control relay in series with one winding of said first lightout relay, a circuit for one winding of said second lightout relay including a front contact of said first lightout relay, a circuit for supplying current to said caution lamp in the event of failure of said proceed lamp, said circuit including a front contact and a normal polar contact of said control relay as well as a back contact of said first lightout relay in series with the other winding of said second lightout relay, another circuit for said caution lamp including a back contact of said control relay in series with said other winding of said second lightout relay, means including a back contact of said control relay for periodically interrupting said last mentioned circuit, means for energizing the other winding of said first lightout relay when said control relay is deenergized as well as when said control relay is energized in the reverse direction, and a circuit for said stop lamp including a back contact of said second lightout relay.
7. In combination, a section of railway track, a signal for said section including a proceed lamp, a caution lamp and a stop lamp, a polarized signal control relay which becomes deenergized when said section is occupied and which becomes energized in the normal or reverse direction in advance with traffic conditions in advance when said section is unoccupied, a lightout relay having two windings, a circuit for one winding of said lightout relay including a front contact and a normal polar contact of said control relay, a circuit for said proceed lamp including a front contact of said lightout relay and a front contact of said control relay, a circuit for said caution lamp including a front contact and a reverse polar contact of said control relay in series with one winding of said second lightout relay, a circuit for said stop lamp including a back contact of said second lightout relay, and means for energizing the other windings of said first and second lightout relays when said control relay is deenergized and energized respectively.
8. In combination, a section of railway track, a signal for said section including a first and a second as well as a third and a fourth lamp, means effective under certain traffic conditions in advance of the signal for lighting said first and second lamps to cause said signal to display an indication, means effective under other certain traffic conditions in advance of the signal to light only said second lamp to cause said signal to display another indication, means effective to light said first lamp if said second lamp is then burned out, means effective to light said third lamp when said section is occupied to cause said signal to display a different indication, and means effective to light said fourth lamp if said third lamp is then burned out to cause said signal to display still a different indication.

GEORGE R. PFLASTERER. 50
